UNITED STATES PATENT OFFICE.

JOHNNIE E. DONOHO, OF MILTON, IOWA.

FABRIC STRETCHING AND CLAMPING DEVICE.

Application filed June 1, 1922. Serial No. 565,261.

To all whom it may concern:

Be it known that I, JOHNNIE E. DONOHO, a citizen of the United States, residing at Milton, in the county of Van Buren and State of Iowa, have invented certain new and useful Improvements in Fabric Stretching and Clamping Devices, of which the following is a specification.

This invention appertains to certain improvements in fabric stretching and clamping devices generally and more particularly to a type of such devices adapted for the stretching of screen wire fabric over door and window frames and the like, and for clamping the fabric in stretched position during the securing or tacking of the same to the frames.

The principal object of the invention is to provide for a device of the class mentioned, and one of an extremely simple, durable and efficient construction and arrangement, such as will be easy to handle in the positioning of the same with respect to the work, conveniently portable from one place to another, rapid in the manipulation and operation of the parts, and cheap to manufacture.

With the foregoing and other equally important objects in view, the invention resides in the certain novel and useful construction and arrangement of parts as will be herein-after more fully described, set forth in the appended claims, and illustrated in the accompanying drawings, in which:

Figure 1 is a rear elevation, partly in section, of a preferred embodiment of the device.

Figure 2 is a top plan view thereof.

Figure 3 is a vertical transverse section taken on the line 3—3 of Figure 1.

Figure 4 is a similar sectional view taken on the line 4—4 of Figure 2.

Figure 5 is another similar view taken on the line 5—5 of Figure 2, and,

Figure 6 is a fragmentary perspective view of one end of the bar used for clamping the fabric in position after the stretching operation thereon.

Referring to the drawings wherein similar characters of reference designate corresponding parts throughout the several views thereof, the embodiment of the invention as shown therein comprises a substantially rectangular base frame formed of front longitudinal bars 10 and 10' and a pair of transverse bars 11 and 11' connecting the oppo-

site ends of the front and rear bars. Equidistantly spaced inwardly of the end bars 11 and 11' are a pair of transverse brace bars 12 and 12' having flanged end portions 13 and 13', respectively, by means of which they are secured in position at the inner side edges of the bars 10 and 10'. (See Figure 5.)

Rising from the opposite ends of the frame or end plates 14 and 14' which are angularly bent at their lower edges to provide inturned flanged portions 15 and 15' set flush in the under face of the ends of the frame, the plates being secured in position by means of bolts 16 passing transversely therethrough and through the end bars 11 and 11' rising from the forward ends of the end plates 14 and 14' are extended portions 17 and 17' which are formed to provide spaced horizontally and inwardly disposed pairs of ribs or flanges 18 and 18', respectively, forming recesses or seats between the same for the reception of the opposite ends of a longitudinally disposed head bar 19, whereby to support the same in spaced parallel relation about the front bar 10.

Extended between the end plates 14 and 14' and disposed in edged relation with respect to the longitudinal center of the upper face of the front frame bar 10 is a clamp bar 20 which has its opposite ends formed to provide reduced vertically disposed portions 21 which slidably engage in vertically slotted openings 22 formed in the end plates 14 and 14' in alinement one with the other and with the vertical centers of the extended portions 17 and 17' thereof. The under longitudinal edge of the clamp bar 20 is serrated or grooved as at 23 to provide a fabric gripping surface thereto, whereby a strip of fabric may be clamped between the roughened face 23 and the upper face of the front frame bar 10. (See Figure 3.)

For raising and lowering the clamp bar 20, a recess 24 is formed on the transverse center of the upper edge face of the same for the reception of the headed end of a bearing screw 25 threaded inwardly of the lower reduced end portion 26 of an operating shaft 27, the reduced end portion 26 of the shaft 27 being swiveled in a bar or plate 28 secured in position on the upper edge of the clamp bar 20 and overlying the recess. The operating shaft 27 passes downwardly through a bore 29 formed centrally

of the headed bar 19, in line with the recess 24, in the clamp bar 20, and with the opening aligned therewith in the bar or plate 28, and is formed to provide an intermediate 5 threaded portion 30 which operates in engagement with a threaded member or nut 31 set flush in the lower face of the head bar 19 with its threaded bore in alignment with the bore 29 of the latter for the purpose.

- 10 The upper end of the operating shaft 27 projects outwardly of the bore 29, in the head bar 19, and through a bearing plate 32, and has on its free end a hand wheel 33 for effecting the operation of the shaft 27 15 correspondingly for the raising and lowering movements of the clamp bar 20.

Coextensive with the front frame bar 10 is a longitudinal bar 34, which is sustained in parallel relation with respect to the front 20 bar 10 by being secured at the forwardly projecting ends of a pair of operating bars 35 and 35', the latter extending transversely of the frame and having their opposite ends 25 slidably mounted in slotted openings extending transversely through the front and rear bars 10 and 10'. The forward ends of the operating bars 35 and 35' are secured in recesses formed in the rear edge of the bar 34 by means of pins 36 and 36' passed vertically through the bar 34 and openings formed in the engaged end portions of the operating bars 35 and 35' for the purpose. In the case of the bar 34 being made of 30 wood, suitable abutting plates 37 and 37' 35 are embedded in the bar 34 at the inner side of the recesses in which the connected ends of the operating bars 35 and 35' are engaged, whereby these ends of the operating bars bear directly against the abutting plates 37 and 37' substantially as is shown 40 in Figures 2 and 4.

For adjusting the bar 34 toward and from its normally close proximity to the opposed edge of the front frame bar 10, and 45 with respect to an opposed edge of a window or door screen frame, the operating bars 35 and 35' are formed at the transverse centers with enlargements having slotted openings 38 formed therein for the engagement through the same of the ends of a pair of actuating bars 39 and 39', respectively. The engaged ends of these actuating bars 39 and 39' are slotted as at 40, and the slots thereof are engaged over pins or bolts 50 41 passed through the enlarged portions of the operating bars 35 and 35' and through the slotted portions therein. Similarly, the brace bars 12 and 12' are formed with enlargements at their transverse centers, and 55 are provided with slotted openings 42 for the passage therethrough of intermediate portions of the actuating bars 39 and 39', which intermediate portions are slotted as at 43, engaged over pins or bolts 44 passed 60 through these enlargements and slotted

openings therein. These actuating bars 39 and 39' are normally disposed one in alignment with the other and have their adjacent ends pivoted as at 45 to a cross head 46 which has a horizontally threaded bore 70 passing therethrough and engaged on an intermediate threaded portion 47 of a hand crank 48. The hand crank 48 is journaled horizontally in the rear frame bar 10' and has its forward end journaled in a bearing plate 49, secured at the inner side of the transverse center of the front frame bar 10, while its rear end is formed to provide a handle portion 48' for its manipulation.

Extending between the end walls 14 and 14', and in spaced horizontal relation at the rear of the clamp bar 20 are a pair of rollers 50 and 51, and medially between these rollers and in a plane below the same is a third roller 52, all of which rollers are journaled on bearing rods secured at their opposite ends in the end plates 14 and 14', and a brace rod 53 is also extended between the latter to prevent any tendency toward a spreading of the rear end portions thereof and to otherwise strengthen the construction as a whole.

In the operation of the device, a window or door screen frame *a* is laid on a flat surface and the stretcher is positioned at one end thereof with the longitudinal bar 34 abutting the adjacent bar or rail of the same. A roll of screen wire fabric will now be placed in position on the rollers 50, 51 and 52, and the free end of the fabric passed forwardly between the rollers 50 and 52 and under the clamp bar 20 and forwardly therefrom over the window or door screen frame to the extreme forward end bar or rail of the latter, where the free edge of the fabric will be tacked or otherwise fastened thereto. The hand wheel 33 will now be manipulated to lower the clamp bar 20 against the fabric *b* to clamp the same between the roughened or grooved face 23 of the clamp bar and the upper face of the front bar 10, when the hand crank 48 will be rotated to cause the cross head 46 to travel rearwardly of the threaded portion 47, which will move the inner ends of the actuating bars 39 and 39' with the same, and force the outer ends thereof in the forward direction when the operating bars 35 and 35' together with the longitudinal bar 34 carried thereby will be projected away from the forward edge of the front frame bar 10, with the result of placing the screen wire fabric under tension and the uniform stretching over the window or door screen frame *a*. When a desired stretching action has been imparted to the fabric *b*, that portion of the same overlying the window or door screen frame *a*, will be tacked or otherwise secured at all desired points thereon, after which, the hand crank 48 may be rotated in a reverse direction to 120

move the cross head 46 forwardly on the threaded portion 47 for the relieving of the tension on the clamped portion of the wire fabric, and the hand wheel 33 also manipulated in a reverse direction for the raising of the clamp bar 20 from its clamping engagement with the wire mesh, so that the wire fabric may now be severed outwardly of the secured end portion thereof on the 10 bar 34 of the device.

For steadyng and otherwise accurately guiding the clamp bar 20 in its raising and lowering movements from and to operative fabric clamping portion, a pair of guide rods 15 54 are projected vertically from the upper edge of the clamp bar 20 and at points equidistantly spaced inwardly from its opposite ends and extend upwardly for sliding engagement through complemental bores 20 formed in the head bar 19. Encircling the guide rods 54 and in interposed relation with respect to the upper and lower edge faces of the clamp bar 20 and the head bar 19 are coiled springs 55 which act to equally tension 25 the opposite ends of the clamp bar 20 and in a manner to assure of the roughened lower edge face of the latter uniformly gripping the fabric underlying the same throughout its extent. Also the opposite end plates 14 30 and 14' are preferably formed to provide horizontally disposed slotted openings 56 whereby to be conveniently grasped by the hands of the operator for facilitating the carrying of the device from one place of 35 operation to another.

From the foregoing, it will be readily apparent that, while a preferred embodiment of the device has been described and illustrated herein in specific terms and details 40 of construction and arrangement, various changes in and modifications of the same may be resorted to without departing from the spirit of the invention, or the scope of the claims appended hereto.

Having thus fully described the invention, what is claimed, is:—

1. A device for the purpose set forth comprising a support for a roll of screen fabric adapted to have the web thereof extended 50 therefrom and connected to a screen frame for the screening of the opening formed by the frame, a screen frame shifting element arranged in advance of said support and adapted to be positioned against the frame 55 when the fabric web is extended forwardly from the roll and support and connected to the frame for screening the opening formed thereby, means carried by said support forwardly of the roll and arranged rearwardly 60 of said element for clamping the extended fabric web inwardly of its connected end, means slidably mounted in said support for connecting said element therewith, oppositely disposed synchronously operating members 65 for shifting said means and said element

with the frame forwardly to draw taut that portion of the web extended forwardly from said clamping means, pin and slot connections between said members and said slideable connecting means, operating means for 70 said members, and means for pivotally connecting said members to the operating means.

2. A device for the purpose set forth comprising a support having means for suspending rearwardly thereon a roll of screen fabric adapted to have its web extended therefrom and forwardly of the support and connected to a screen frame for screening the opening formed by the frame, a screen 80 frame shifting element arranged in advance of said support and adapted to be interposed between the support and the screen frame when the fabric web is extended forwardly from the roll and support and connected to the frame for screening the opening formed by the frame, a vertically movable clamping member carried by said support and arranged rearwardly of said element for clamping the extended web inwardly of its 85 connected end, a pair of operating bars slidably mounted in said support, projecting forwardly therefrom and coupled with said element for shifting it and the screen frame forwardly to draw taut that portion of the 90 web extended forwardly from said clamping member, and means for operating said bars.

3. A device for the purpose set forth comprising a support having means for suspending rearwardly thereon a roll of screen 100 fabric adapted to have its web extended therefrom and forwardly of the support and connected to a screen frame for screening the opening formed by the frame, a screen frame shifting element arranged in advance of said support and adapted to be interposed between the support and the screen frame when the fabric web is extended forwardly from the roll and support and connected to the frame for screening the opening formed by the frame, a vertically 105 movable clamping member carried by said support and arranged rearwardly of said element for clamping the extended web inwardly of its connected end, a pair of operating bars slidably mounted in said support, projecting forwardly therefrom and coupled with said element for shifting it and the screen frame forwardly to draw taut that portion of the 110 web extended forwardly from said clamping member, a pair of oppositely disposed synchronously operating members engaging with said bars for shifting them and said element with the screen frame forwardly to draw taut that portion of the web extended forwardly from said clamping means, and operating means for 115 said members.

4. A device for the purpose set forth comprising a support having means for sus- 120

pending rearwardly thereon a roll of screen fabric adapted to have its web extended therefrom and forwardly of the support and connected to a screen frame for screening the opening formed by the frame, a screen frame shifting element arranged in advance of said support and adapted to be interposed between the support and the screen frame when the fabric web is extended forwardly from the roll and support and connected to the frame for screening the opening formed by the frame, a vertically movable clamping member carried by said support and arranged rearwardly of said element for clamping the extended web inwardly of its connected end, a pair of operating bars slidably mounted in said support, projecting forwardly therefrom and coupled with said element for shifting it and the screen frame forwardly to draw taut that portion of the web extended forwardly from said clamping member, a pair of oppositely disposed synchronously operating members engaging with said bars for shifting them and said element with the screen frame forwardly to draw taut that portion of the web extended forwardly from said clamping means, and operating means for said members, said members pivotally connected with said operating means and having pin and slot connections with said bars.

5. A device for the purpose set forth comprising a support having means for suspending rearwardly thereon a roll of screen fabric adapted to have its web extended

therefrom and forwardly of the support and connected to a screen frame for screening the opening formed by the frame, a screen frame shifting element arranged in advance of said support and adapted to be interposed between the support and the screen frame when the fabric web is extended forwardly from the roll and support and connected to the frame for screening the opening formed by the frame, a vertically movable clamping member carried by said support and arranged rearwardly of said element for clamping the extended web inwardly of its connected end, a pair of operating bars slidably mounted in said support, projecting forwardly therefrom and coupled with said element for shifting it and the screen frame forwardly to draw taut that portion of the web extended forwardly from said clamping member, a pair of oppositely disposed synchronously operating members engaging with said bars for shifting them and said element with the screen frame forwardly to draw taut that portion of the web extended forwardly from said clamping means, and operating means for said members, said members pivotally connected with said operating means and having pin and slot connections with said bars, and said members further having pin and slot connections with said support.

In testimony whereof, I affix my signature hereto.

JOHNNIE E. DONOHO.
